JAMES L. HOWARD, OF HARTFORD, CONNECTICUT.

Letters Patent No. 98,967, dated January 18, 1870.

IMPROVEMENT IN CAR-DOOR LOCKS.

The Schedule referred to in these Letters Patent and making part of the same.

To all whom it may concern:

Be it known that I, JAMES L. HOWARD, of Hartford, in the county of Hartford, and State of Connecticut, have invented a new and useful Improvement in Freight-Car Lock; and I do hereby declare that the following is a full, clear, and exact description thereof, which will enable others skilled in the art to make and use the same, reference being had to the accompanying drawings, forming part of this specification.

This invention relates to locks for fastening the doors of railroad freight-cars, having especial reference to the locks, where the bolt secures a hasp; and consists in combining a longitudinally-ribbed bolt, having a recessed arrow-head thereon, with hooked catches, as will be hereinafter more particularly specified.

In the accompanying drawing—

Figure 1 represents a top view of the lock, so far as it relates to my invention.

Figure 2 is an edge view of the same.

Similar letters of reference indicate corresponding parts.

A is the lock-plate, to which is attached the lock proper B, containing the mechanism, (springs, wards, tumblers, &c.,) by which the hook-jaws C C are operated or spread, so as to release the bolt D.

As these locks have hitherto been made, the ends of the jaws C, by which the bolt D is fastened, have been made with square shoulders, instead of hooks, and the arrow-head E of the bolt has been made to correspond. Such a construction has not prevented the lock from being tampered with, and the bolt withdrawn, by expert burglars.

As this connection is a vital point in the lock-fastening, I have, with a view of rendering it perfectly safe, formed a hook-connection, as seen at F F, fig. 1, so that any friction which might be produced by drawing upon the bolt, and tapping the same, will only serve to draw the jaws toward each other, instead of allow-

ing them to be spread. This hook-connection F has been found a perfect protection.

G is a longitudinal rib on the bolt, to prevent the same from having lateral play, and to guide it in a right line to its true position between the hooked catches. This rib may be laterally perforated, to receive a wire, to which a seal may be then attached.

Through this hole I pass a wire, to which the seal is attached for sealing the lock. By attaching the seal to the bolt, by means of a wire, in this prominent position, the seal can never be overlooked, as any tampering therewith would be at once exposed to view.

I I are bands or clasps, securely riveted to the plate A, through which clasp the bolt D passes.

The lock is placed vertically on the door-frame or casing, with the bolt D hanging down.

The hasp of the door is closed over the plate A, (having a slot or mortise in it, which receives the clasp I,) and occupies the spaces J J, beneath the bolt.

When the hasp is thus placed, the bolt is shoved up through the clasps I I, and into the jaws C C, the key being used only in unlocking.

When the car-door is to be opened, the key is inserted and turned, and the jaws spread apart. By this proceeding the bolt will be raised, and will fall out by its own gravity.

Having thus described my invention, I claim as new, and desire to secure by Letters Patent—

A freight-car lock, provided with hooks F F, and a bolt, having arrow-head E, recessed under its wings, and longitudinal rib G, all arranged as and for the purpose specified.

The above specification of my invention signed by me, this 8th day of October, 1869.
